FILE HOLDER OR GUIDE

Walter G. Shearer, Wenatchee, Wash.

Application January 5, 1948, Serial No. 563; cointerpart of U.S. Patent No. 2,438,456, filed January 5, 1948, and issued January 13, 1948.

4 Claims. (Cl. 76—36)

This invention relates to an improved holder particularly well adapted for holding and guiding files in a device for filing circular saws covered in my application Serial No. 562 filed January 5, 1948.

In filing saws, particularly circular saws, various types of triangular, flat and round files are required in order to shape and sharpen the saw teeth, which not only require the inclination, bevel and pitch angles of the files to be accurately controlled but in many instances require shaping along curved surfaces. In said application it has been set forth that the filing device is equipped to hold the files at various adjusted angles of inclination, bevel and pitch thru the instrumentality of a file holder which is guided in a slotted guide held at such angles as required by a saw to be filed. The present invention particularly relates to the file holder for that purpose, tho not necessarily limited thereto.

The principal object of the present invention is to provide such a file holder which is provided with what might be termed universal gripping means for holding different types of files so as to extend longitudinally therefrom as will be set forth in detail.

Further features, objects and advantages of my invention will appear in the following detailed description supplemented by the accompanying drawings illustrating a highly satisfactory embodiment of my invention.

In the drawings:

Figs. 1 and 2 are perspective views of the file holder in accordance with my invention, the views being taken from opposite ends of the holder to more fully illustrate the structure at the clamp end thereof.

Fig. 3 is a plan view thereof showing a triangular file held by the holder.

Fig. 4 is a transverse vertical sectional view taken on line 4—4 of Fig. 3.

Fig. 5 is a fragmentary horizontal sectional view taken on line 5—5 of Fig. 4.

Fig. 6 is a similar horizontal sectional view of that part of the holder without the file and clamp screw.

Fig. 7 is a fragmentary horizontal transverse sectional view similar to Fig. 5, with the end of a flat type of file gripped in the holder clamp.

Fig. 8 is a perspective view of an adapter for

cooperating with the file holder for gripping the shank end of a file.

Fig. 9 is a fragmentary horizontal transverse sectional view, similar to Fig. 5 with the adapter and the shank end of a flat file gripped in the holder.

Referring to the drawings in general the file holder in accordance with my invention comprises a longitudinal shank or bar 10 of uniform rectangular cross section for sliding in the file guide member of the device for filing circular saws as set forth in my aforesaid copending application, or for other uses such as a file handle. The file holding end of bar 10 is provided with a clamp 11 and is slotted at 12 for cooperating with the clamp and an adapter or keeper 13 shown in Fig. 8 may also cooperate therewith.

The file holding clamp 11 comprises a channel shaped element with its ends 14 welded to the sides of bar 10 adjacent to its end as best shown in Fig. 4, and the mid upper portion has a threaded aperture therethru for receiving a clamping screw 15 so positioned as to engage a portion of a file 16, for holding it in the slot 12 in the end 25 of bar 10 underlying clamp 11.

In saw filing for sharpening the teeth various types of triangular files are employed in most instances so as shown in Figs. 1, 2, 4 and 6, slot 12 is tapered to conform with the surfaces of such 30 a triangular file 16 so that the third side 17 of file 16 is in a horizontal position for engagement by the inner end of clamping screw 15.

Thus with file 16 in clamped position and provided with a handle 18 as shown in Fig. 3 the file 35 is equipped with the holder for use in the device for filing saws or it may be employed as a handle or the like.

The file holder is adapted to grip a flat file 19 with equal facility as shown in Fig. 7. The sides 40 20 of this file engage the sides of clamp 11 and clamping screw 15 maintains the file in the required position.

As shown in Figs. 8 and 9, the adapter or keeper 45 13 is provided for gripping the shank or tang end 21 of a file 22 as may be desired in some instances for operating it in a saw filing device, a flat file for jointing operations, or as a handle for a file 22 extending from its shank 21. The adapter 13 as shown comprises a longitudinal metal plate having 50 downwardly extending projections 24 at one

end which engage the sides of bar 10 of the file holder. Adjacent the same end are inner upwardly extending projections 25 which may be struck up from the plate element as shown. These latter projections 25 are adapted to engage the sides of file shank 21 adjacent its end and when clamping screw 15 is turned into place engaging file shank 21 at a distance therefrom, the file is securely held in the holder.

The file holder thus is adapted for holding various types of files operating as a holder for a saw filing device, a handle or otherwise.

I claim:

1. A file holder comprising, an elongated rectangular bar, a channel shaped clamping member having a web portion between depending side flanges, means integrally connecting the inner edges of the flanges of said clamping member to the edges of the bar at one end thereof so as to provide a longitudinal slot above the bar, and a clamping screw element extending thru the web portion of said channel member toward the upper side of the bar for engaging and clamping a file therein, said bar under said channel shaped clamping member having a downwardly tapered slot extending longitudinally therethrough, through which the lower edge portion of a triangular file will project when secured in the holder by the clamping screw.

2. A file holder comprising, an elongated rectangular bar, a channel shaped clamping member integrally connected to one end of said bar so as to provide a longitudinal slot above the bar, said bar having a tapered longitudinal slot extending entirely through the end of the bar underlying said channel member for engagement with two sides of a triangular file and a clamping screw element extending thru the mid portion of said channel member toward the slot in the bar for engaging the other side of the triangular file and clamping the file therein.

3. A file holder comprising, an elongated rectangular bar, a channel shaped clamping mem-

ber integrally connected to one end of said bar so as to provide a longitudinal slot above the bar, a clamping screw element extending thru the mid portion of said channel member toward the side of the bar for engaging and clamping a file therein, an adapter for engaging the tang end of a file beyond the clamping means comprising a longitudinal plate member insertable in said channel slot formation, and means extending from said plate for engaging the sides of a file tang adjacent to its end.

4. In a combination with a file holder comprising an elongated rectangular bar, a channel shaped clamping member integrally connected to one end of said bar so as to provide a longitudinal slot above the bar, and a clamping screw element extending thru the mid portion of said channel member toward the side of the bar for engaging and clamping a file therein, an adapter for holding and centering the tang end of a file longitudinally of the bar comprising a longitudinal plate member for overlying the bar and extending one end into the clamping channel, said bar at its other end having lateral lugs extending downwardly so as to engage the sides of the bar, and a pair of lugs struck upwardly from the central portion of said plate adjacent to the same end for engaging the sides of a file tang end and cooperating with the clamping screw for maintaining the file in a longitudinally extending direction from the file holder.
